(57) **CLAIM**

The ornamental design for a box, as shown and described.

DESCRIPTION

FIG. 1 is a top perspective view of a first embodiment of a box in a folded configuration;

FIG. 2 is a front side view of the box of FIG. 1;

FIG. 3 is a back side view of the box of FIG. 1;

FIG. 4 is a left side view of the box of FIG. 1;

FIG. 5 is a right side view of the box of FIG. 1;

FIG. 6 is a top plan view of the box of FIG. 1;

FIG. 7 is a bottom plan view of the box of FIG. 1;

FIG. 8 is a top plan view of the box of FIG. 1 in an unfolded blank configuration, where dot-dot-dash lines represent unfolded fold lines of the box;

FIG. 9 is a cross-section view of the box of FIG. 1, taken along line 9-9 in FIG. 2;

FIG. 10 is a top perspective view of a second embodiment of a box in a folded configuration;

FIG. 11 is a front side view of the box of FIG. 10;

FIG. 12 is a back side view of the box of FIG. 10;

FIG. 13 is a left side view of the box of FIG. 10;

FIG. 14 is a right side view of the box of FIG. 10;

FIG. 15 is a top plan view of the box of FIG. 10;

FIG. 16 is a bottom plan view of the box of FIG. 10;

FIG. 17 is a top plan view of the box of FIG. 10 in an unfolded blank configuration, where dot-dot-dash lines represent unfolded fold lines of the box;

FIG. 18 is a cross-section view of the box of FIG. 10, taken along line 18-18 in FIG. 11;

FIG. 19 is a top perspective view of a third embodiment of a box in a folded configuration;

FIG. 20 is a front side view of the box of FIG. 19;

FIG. 21 is a back side view of the box of FIG. 19;

FIG. 22 is a left side view of the box of FIG. 19;

FIG. 23 is a right side view of the box of FIG. 19;

FIG. 24 is a top plan view of the box of FIG. 19;

FIG. 25 is a bottom plan view of the box of FIG. 19;

FIG. 26 is a top plan view of the box of FIG. 19 in an unfolded blank configuration, where dot-dot-dash lines represent unfolded fold lines of the box;

(Continued)

FIG. 27 is a cross-section view of the box of FIG. 19, taken along line 27-27 in FIG. 20;
 FIG. 28 is a top perspective view of a fourth embodiment of a box blank in a folded configuration;
 FIG. 29 is a front side view of the box of FIG. 28;
 FIG. 30 is a back side view of the box of FIG. 28;
 FIG. 31 is a left side view of the box of FIG. 28;
 FIG. 32 is a right side view of the box of FIG. 28;
 FIG. 33 is a top plan view of the box of FIG. 28;
 FIG. 34 is a bottom plan view of the box of FIG. 28;
 FIG. 35 is a top plan view of the box of FIG. 28 in an unfolded blank configuration, where dot-dot-dash lines represent unfolded fold lines of the box; and,
 FIG. 36 is a cross-section view of the box of FIG. 28, taken along line 36-36 in FIG. 29.
 The dot-dot-dash lines in the figures depict fold lines and do not form a part of the claimed design.
